Term of patent 14 years

(Cl. D71—1)

FIG.1

FIG.2

FIG. 3

FIG. 1 is a top plan view of a helicopter embodying our new design with the broken line portions omitted for clarity;

FIG. 2 is a side elevational view thereof; and

FIG. 3 is a front elevational view thereof.

The dominant features of our design reside in the portions shown in full lines, with the broken line portions being broken away for convenience of illustration.

We claim:

The ornamental design for a helicopter, substantially as shown and described.
